UNITED STATES PATENT OFFICE.

EDWARD KLINGBEIL, OF OAK PARK, ILLINOIS.

HEATER.

Application filed August 23, 1926. Serial No. 130,976.

This invention relates to heaters especially adapted for use in heating water, although not in any sense restricted to such use.

Briefly stated, an important object of the invention is to provide a heater having novel means whereby the heating coil is mounted in the range of heat from the products of combustion of either or both of separate sources of heat such as a gas burner or a fire of coals, wood, trash or other combustible material.

A further and equally important object of the invention is to provide a heater of the character specified in which the draft through the heater may be reversed for operation under various conditions.

Other objects and advantages will be apparent during the course of the following description.

20 In the accompanying drawings forming a part of this application and in which like numerals are employed to designate like parts throughout the same,

Figure 1 is a vertical sectional view through the improved heater;

Figure 2 is a perspective of the heater;

Figure 3 is a fragmentary perspective illustrating an outlet connection embodied in the invention;

30 Figure 4 is a group perspective illustrating several of an annular series of ribs embodied in the invention;

Figure 5 is a horizontal sectional view taken on line 5—5 of Figure 1;

35 Figure 6 is a horizontal sectional view taken on line 6—6 of Figure 1.

In the drawing the numeral 5 designates a shell or heater casing mounted upon the ash pit or base portion 6, the base portion in turn being supported by legs 7. In carrying

40 out the invention a flue pipe 8 is attached to the upper portion of the casing 5 and communicates either with an annular chamber 9 or a retort tube 10. The retort tube 10 is arranged centrally within the casing 5 in

45 spaced relation to the side wall thereof and communication between the tube and the flue is controlled by means of a combined slide valve and closure 11. Figure 1 clearly illustrates that when the combined slide valve and closure is in what might be said to be its open position, it cuts off direct communication between the retort tube and the flue

50 and at the same time allows of the admission of air to the retort tube by way of an opening 14. When the slide valve 11 is posi-

tioned as shown in Figure 2, there will be a down draft through the tube 10 and an up draft through the annular chamber 9 will be permitted.

On the other hand, when the combined slide valve and closure 11 is in closed position, the admission of air by way of the opening 14 is cut off and direct communication between the tube 10 and the flue pipe 8 is established. It will thus be seen that the member 11 functions as a means for controlling admission of air to the tube 10 by way of the opening 14 and has a damper for controlling communication between the tube 10 and the flue 8.

The retort tube 10 is surrounded by an annular series of ribs 18, the lower portions of which are securely held in place by a band 20 or other suitable fastening device and the upper portions of the ribs are engaged by stops 22 by which the tube 10 is supported. Attention is now directed to Figure 4 which illustrates that the upper portions of the ribs 18 are provided with laterally projecting 80 heads or shoulders 24 which act to uniformly space the ribs about the retort tube.

The ribs 18 carry a plurality of radial pegs or lugs 26 upon which the convolutions of a coil 28 are mounted. It will be observed that the ribs 18 may be positioned within the coil 28 and the lugs 26 engaged with the convolutions of the coil preparatory to the application of the retort tube 10. In other words, in originally assembling the 90 parts 10, 18 and 28, the lugs 26 of the ribs are engaged with the convolutions of the coil and the ribs are then slipped onto the retort tube as a unit, after which they may be locked in place by the band 20 and the retainers 22.

Water may be supplied to the coil by a pipe 30 and water may be discharged by the pipe 31, both of which may have connection in the usual and well known manner with a suitably sized boiler 34.

Referring again to Figure 1, it will be seen that the grate 16 is mounted on supports 36 and that an annular gas burner 38 is also mounted upon the supports outwardly of the grate. A gas supply pipe may be connected to the annular gas burner at one or more places, a suitable number of connections being provided for this purpose.

In the operation of the improved heater, fuel such as wood, trash or coal is placed upon the grate 16 and ignited and in case

the burner 38 is operating at the time combustion is taking place within the retort tube 10, a down draft in the tube 10 and an up draft through the chamber 9 will be established. Of course, communication between the lower portion of the retort tube 10 and the lower portion of the chamber 9 is by way of the ash pit 6. To provide for this down draft, however, it is necessary to move the combined closure and damper 11 to the open position illustrated in Figure 1. The heat from the fuel upon the grate and the gas burner will effectively heat the water in the coil.

15. In case the gas burner is not operating, an up draft through the tube 10 may be provided by moving the member 11 to its closed position and by opening a draft door 46 in the ash pit. When the member 11 is thus closed, the admission of air by way of the opening 14 is prevented and direct communication is established between the retort tube 10 and the pipe 8. It might be noted that the movement of the member 11 is controlled by a knob 47 which may be easily grasped by the fingers and which in addition to functioning as a knob acts as a stop.

A heater constructed in accordance with this invention may be economically manufactured and by reason of the large number of fuels which may be employed either alone or in conjunction with gas, an extremely efficient heater is provided.

Having thus described the invention, what is claimed is:

1. A heater comprising a casing, a grate in the bottom thereof, a tube in said casing and spaced from the walls thereof, said cas-

ing having a top provided with an air inlet and an outlet flue, a plate slideable over the top of said tube and closing communication between said tube and outlet flue in one position of the plate, said plate being formed to close communication between said tube and inlet and simultaneously open communication between said tube and outlet flue in another position of the plate, and means on said grate for supporting said tube.

2. A heater comprising a cylindrical casing having a closed top provided with an outlet flue and an air inlet, a grate in the lower end thereof, an open ended tube supported on said grate and concentric with said casing, water tubes surrounding said tube, and means at the top of said tube for selectively changing said tube from an air inlet down-draft conduit to a flue outlet conduit from the grate.

3. In a heater, a casing, a grate in the lower end thereof, an open ended tube in the casing above said grate, water coils surrounding said tube, and uprights carried by said grate and forming a common support for said tube and water coils.

4. A water heater comprising a casing, a grate in the lower end thereof, a draft tube in said casing above the grate, a plurality of grate carried uprights disposed around said tube and having supporting connection with the upper end of the tube, vertically spaced lugs extending laterally from said uprights between the tube and casing, and water coils supported on said lugs.

In testimony whereof I affix my signature.

EDWARD KLINGBEIL.
